OTHER PUBLICATIONS

U.S. Appl. No. 29/864,173 entitled "Lever", filed May 12, 2022, 8 pages.

Primary Examiner — Lauren R Calve

(74) Attorney, Agent, or Firm — Merchant & Gould P.C.

(57) **CLAIM**

The ornamental design for a lever, as shown and described.

DESCRIPTION

FIG. 1 is a front perspective view of a lever showing our new design;

FIG. 2 is a front view of the lever of FIG. 1;

FIG. 3 is a rear view of the lever of FIG. 1;

FIG. 4 is a right side view of the lever of FIG. 1;

FIG. 5 is a left side view of the lever of FIG. 1;

FIG. 6 is a top view of the lever of FIG. 1; and,

FIG. 7 is a bottom view of the lever of FIG. 1.

Any portion of the article depicted in broken lines forms no part of the claimed design. Broken lines formed by equal length dashes show unclaimed portions of the design.

1 Claim, 5 Drawing Sheets(56)
